(71) Applicant: **Ján Baráni**, Liptovsky Mikulás (SK)

* cited by examiner

(72) Inventor: **Ján Baráni**, Liptovsky Mikulás (SK)

Primary Examiner — George D Kirschbaum

(**) Term: **15 Years**

(21) Appl. No.: **35/501,051**

(57) **CLAIM**

(22) Filed: **Feb. 29, 2016**

The ornamental design for cover of meteorological instruments, as shown and described.

(80) **Hague Agreement Data**

Int. Filing Date: **Feb. 29, 2016**

DESCRIPTION

Int. Reg. No.: **DM/090822**

1.-3. Parts of covers of meteorological instruments
4. Cover of meteorological instruments

Int. Reg. Date: **Feb. 29, 2016**
